James S. Wigmore

UNITED STATES PATENT OFFICE.

JAMES S. WIGMORE, OF MONTICELLO, INDIANA.

CRUTCH-TOP.

SPECIFICATION forming part of Letters Patent No. 242,090, dated May 24, 1881.

Application filed December 22, 1880. (Model.)

To all whom it may concern:

Be it known that I, JAMES S. WIGMORE, a citizen of the United States, residing at Monticello, in the county of White, in the State of Indiana, have invented a certain new and useful Improvement in Crutches; and I do hereby declare that the following is a full, clear, and exact description of the invention, which will enable others skilled in the art to which it applies to make and use the same.

The object and nature of my invention are to preserve the crutch and prevent its destruction from the use of tacks or small nails, which are now used to secure the arm-pads to the crutch. The repeated driving of the tacks into the crutch frequently splits it and renders it useless.

My invention obviates the necessity of using tacks or nails to secure the arm-pads to the crutch altogether, and instead of weakening the crutch it strengthens and makes it more durable.

It consists of a metal box, a detailed description of which is hereinafter given.

The drawing accompanying this specification, and which is made a part hereof, represents the top of a crutch, partly in section.

A is the metal box; B, the hinged part; C, the cloth or leather ends of the arm-pads; D, a screw, securing both; E, the crutch-top; *a*, the rivet or pintle on which the hinged part turns; *b*, serrations on inside of hinged part; *d*, serrations on crutch-top.

The metal box is made from two and one-half to three inches in length, and of width and depth sufficient to pass easily over the crutch-top. Smooth rounded projections are

formed on three outer sides, leaving the inner side or bottom of the box smooth and flat. These projections extend slightly upward from the inside when the box is in place on the crutch. On the outside a lid or hinged part is formed to fit neatly inside the box, so that when in place on the crutch the outside presents a smooth surface. At the upper end of the box small holes are made through the rounded projections, and a corresponding hole through the rounded projection which forms one of the three sides, as above described. Through these holes in the box and lid a metal rivet or pintle passes, upon which the lid turns. Serrations are made in the lid or hinged part and corresponding serrations in the crutch-top. The cloth or leather ends of the arm-pads are passed over the top of the crutch and through the box, the ends of which are left open to receive them. The lid or hinged part is then closed on the outer side of the crutch-top and secured by a screw, which passes through the lower part of the lid or hinged part, the cloth or leather ends of the arm-pads, the crutch-top, and the bottom of the box.

Having thus described my invention, I claim—

The box with serrated hinged lid in combination with crutch-top, substantially as described in the foregoing specification.

In testimony that I claim the foregoing I have hereunto set my hand and seal this 8th day of December, A. D. 1880.

JAMES S. WIGMORE. [L. S.]
